US0D1031095S

(12) **United States Design Patent** (10) Patent No.: **US D1,031,095 S**
(45) Date of Patent: ** Jun. 11, 2024

(54) **SLAB**

(71) Applicant: **American Quartz Max Corp.**,
Barstow, CA (US)

(72) Inventor: **Shichun Ou**, Barstow, CA (US)

(**) Term: **15 Years**

(21) Appl. No.: **29/846,237**

(22) Filed: **Jul. 14, 2022**

(51) LOC (14) Cl. **25-01**

(52) U.S. Cl.
USPC **D25/151**; D5/43

(58) **Field of Classification Search**

USPC D25/151, 138, 48.8, 153, 157, 164, 119;
D5/43, 44, 62

CPC E04B 2/72; E04B 2/74; E04B 9/00; E04B
